(57) **CLAIM**

The ornamental design for a drain plug screen as shown and described.

DESCRIPTION

FIG. 1 is a perspective view of a sink apron showing my new design;

FIG. 2 is a side elevational view thereof;

FIG. 3 is a top plan view thereof;

FIG. 4 is a bottom plan view thereof; and,

FIG. 5 is an exploded perspective view of the drain plug screen, showing the drain plug having the drain plug screen disposed there around pulled away from the drain body. The broken lines shown in the drawings represent portions of the drain plug and drain body that form no part of the claimed design, but show the environment of the drain plug screen.
